(57) **CLAIM**

The speaker sound bar with bolt on mounts, as shown and described.

DESCRIPTION

FIG. 1 is a front and right side perspective view of a speaker sound bar with bolt on mounts embodying our new design; FIG. 2 is a front elevation view thereof;

FIG. 3 is a rear elevation view thereof;

FIG. 4 is a cross-sectional view thereof taken between axes A-A and B-B of FIG. 3;

FIG. 5 is a left-side elevation view thereof;

FIG. 6 is a right-side elevation view thereof;

FIG. 7 is a top plan view thereof; and,

FIG. 8 is a bottom plan view thereof.

The broken lines shown are included for the purpose of illustrating portions of the speaker sound bar with bolt on mounts that form no part of the claim.

1 Claim, 3 Drawing Sheets
